COMBINED DISPLAY AND STORAGE STAND

Henry Ullmann, 453 Wellingborough Road,
Northampton, England

Filed Sept. 6, 1963, Ser. No. 76,504

Claims priority, application Germany Mar. 12, 1963

Term of patent 14 years

(Cl. D80—9)

FIG. 1

FIG. 3

FIG. 1 is a perspective view of the combined display and storage stand, embodying my new design;

FIG. 2 is a top plan view thereof; and

FIG. 3 is a fragmentary perspective view of a portion of one of the display columns.

I claim:

The ornamental design for a combined display and storage stand, as shown.
